UNITED STATES PATENT OFFICE.

LESTER R. WELLMAN, OF CHICAGO, ILLINOIS.

DESIGN FOR A BOWL-HOOK FOR LIGHTING-FIXTURES.

58,003.

Specification for Design.

Patented May 24, 1921.

Application filed October 5, 1920. Serial No. 414,874. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Bowl-Hook for Lighting-Fixtures, of which the following is a specification, reference being had to the accompanying drawings, wherein—

Figure 1 is a perspective view of a bowl hook for lighting fixtures showing my new design, and

Fig. 2 is a side elevation of the same.

I claim as my invention:

The ornamental design for a bowl hook for lighting fixtures, as shown.

LESTER R. WELLMAN.
